[57] CLAIM

The ornamental design for a billiard table aiming system, as shown and described.

DESCRIPTION

FIG. 1 is an exploded perspective view of a billiard table aiming system showing our new design; consisting of a monitor, billiard table and a display screen;

FIG. 2 is a top view of a monitor thereof; shown separately for clarity;

FIG. 3 is a bottom view thereof;

FIG. 4 is a right side view thereof;

FIG. 5 is a left side view thereof;

FIG. 6 is a front view thereof;

FIG. 7 is a rear view thereof;

FIG. 8 is top view of a billiard table thereof; shown separately for clarity;

FIG. 9 bottom view thereof;

FIG. 10 is a left side view thereof; the right side view is a mirror image thereof;

FIG. 11 is a front view thereof; the rear view is a mirror image thereof;

FIG. 12 is a front view of a display screen thereof; shown separately for clarity;

FIG. 13 is a rear view thereof;

FIG. 14 is a left side view thereof; the right side view is a mirror image thereof;

FIG. 15 is a top view thereof; and,

FIG. 16 is a bottom view thereof.
